MOVING STAIRWAY HANDRAIL SUPPORT-
ING DEVICE

Samuel Gustave Margles, Brooklyn, N. Y., assignor to Otis Elevator Company, New York, N. Y., a corporation of New Jersey

Application September 2, 1950, Serial No. 182,954

2 Claims. (Cl. 198—16)

1

The invention relates to handrails of moving stairways and especially to the driving of the handrails.

Moving stairways are provided with moving handrails for the convenience of persons using the stairways. Two handrails are provided, one on each side of the stairs, and are arranged to be driven in synchronism with the steps. It has been the practice for a great many years to provide a traction drive for the handrails. In these arrangements, the handrail passes around newel wheels at the ends of the stairway. There are certain advantages in providing a single wrap traction drive for each handrail, that is one in which the traction is provided solely at the driving newel wheel at one end of the stairway. In the preferred construction, on the upper run the handrails slide on guides between the newel wheels. On the return run, at the upper end of the stairway the handrails pass around tensioning devices with a reverse bend and extend from the tensioning devices down the incline to the lower end of the stairway. The invention is directed to tensioning devices for the handrail return runs.

The object of the invention is to provide a reverse bend tensioning device for handrails which minimizes friction drag on the handrail on the return run and obviates damage to the handrail.

In carrying out the invention according to the preferred arrangement, a plurality of closely spaced rollers are arranged on each side of the stairway in an arc of large radius extending from adjacent the upper newel wheel to well down the incline of the stairway. These rollers are rotatably mounted on an arcuate support adjustably mounted on the stairway balustrade framework. The back of the handrail runs over these rollers with a reverse bend, being tangent to the newel wheel and to the arc of the rollers adjacent the newel wheel at a point depending on the adjusted position of the arcuate support. Also the handrail is tangent to the arc of the rollers at the handrail incline, the point of incline tangency also depending upon the position of the arcuate support. The arcuate support is adjusted to take up on the return run handrail incline so as to provide the desired traction for the driving of the handrail.

Features and advantages of the invention will be seen from the above statements and from the following description and appended claims.

In the drawings:

Figure 1 is a diagrammatic representation in 55

2

side elevation of a moving stairway, illustrating the preferred embodiment of the invention.

Figure 2 is a view in longitudinal section of the upper end of the stairway of Figure 1, parts being shown diagrammatically.

Figure 3 is an enlarged sectional view taken along line 3—3 of Figure 2; and

Figure 4 is a view taken along line 4—4 of Figure 2.

Referring to Figure 1, the moving stairway extends between the lower landing 1 and an upper landing 11. In the arrangement illustrated, the stairway comprises an endless series of steps 12 driven at the upper end of the stairway by means of sprocket wheels through running gear chains. These sprocket wheels are mounted on and driven by the main drive shaft 13 of the stairway. This drive shaft in turn is driven by an electric motor 14 through reduction gearing 15, this gearing including a driven gear 16 on shaft 13, an idler gear 18, a driving gear 20 in turn driven by the motor through a worm and gear reduction (not shown).

The stairway has two endless moving handrails, one on each side thereof. These handrails are driven from motor 14 to operate in synchronism with the steps. The handrail 25 for but one side of the stairway is illustrated. The driving newel wheel 26 for the handrail is mounted on a stub shaft 27. The newel wheel is driven by means of a sprocket 30 bolted to the wheel, in turn driven through sprocket chain 31 driven by sprocket wheel 32 of the main drive shaft. The sprocket chain 31 passes over a pair of deflector sprockets 33, adjustably mounted to provide the desired tension. The handrail on the other side of the stairway is driven in a similar manner from shaft 13.

The handrails are C-shaped in cross section (see Figure 3) and are of rubber reinforced with canvas. The rim of each of the driving newel wheels has a rubber tire 34 vulcanized thereto to provide the desired traction. Each handrail has a steel tape 35 moulded therein of a width co-extensive with the flat portion of the handrail. The ends of the tape are secured together at the same time that the ends of the handrails are joined to form a continuous loop. This construction obviates any undesirable stretching of the handrail.

On the upper or exposed run, each handrail is guided between the newel wheels on a guide 36. The handrails fit over the guides which are shaped to slidably support the handrails and to guide them laterally. On the return run, the

back of each handrail, that is the flat portion of the handrail outer surface, passes over a reverse bend tensioning device 37 adjustably secured to the stairway framework.

Referring to Figures 2, 3 and 4, each tensioning device comprises a plurality of rollers 40 mounted on an arcuate support 41 in the form of a segment of a large circle. These rollers are of plastic material, such as a phenolic resin compound, and are provided with ball bearings 42 supported on pins 43 mounted on support 41. The arcuate support in cross section is in the form of an angle and is provided with a pair of mounting angles 44, secured to the vertical leg thereof as by welding. Bolts 45 in the ends of angles 44 clamp the arcuate support to a plate 46 secured to the balustrade framework 47 adjacent the driving newel wheel 26. The plate is provided with slots 48 through which the bolts extend and arranged at an angle to the stairway incline to permit the position of the tensioning device to be readily adjusted. Troughs 49 are welded to plate 46 in back of the slots to prevent turning of the bolt heads. A screw 50 extends through a bracket 51 on the arcuate support and a bracket 52 on plate 46 and is provided with nuts 53 at each end for cooperating with the brackets for effecting the adjustment. The slots 48 are terminated at an upper point such that with the arcuate support at the top of the slots, the handrail is just tangent to the second or third supporting rollers from the ends. In lower positions of the support the handrail is tangent at rollers farther in from the ends, the particular points of tangency being dependent on the position of the arcuate support. Thus the handrail is led on and off the tensioning device without being bent.

To insure the handrail running on the rollers, a short arcuate guide 54 is provided for the handrail above the arcuate support. The handrail fits over the guide which is shaped to guide the handrail laterally should it tend to deviate sidewise. This guide is supported by brackets 55 mounted on the arcuate support.

With the single wrap traction drive handrail, the handrails may be formed as continuous loops in the factory and slid into place before the side panels of the balustrading are installed. In forming the loops, the ends of the handrail are vulcanized together. In this process the ends of the steel tape insert are also vulcanized together as by providing overlapping ends coated with rubber cement. In installing a handrail, it is pulled sidewise over its guides 36 on the upper run, led over the newel wheels at the ends of the stairway and then placed over the tensioning device 37. The guide 54 is then sprung into place and mounted on the arcuate support. When these operations have been completed, the tensioning device is adjusted to provide the desired tension in the handrail.

The elimination of sharp bending of the handrail as it passes onto and off the tensioning device minimizes the possibility of damage to the handrail and its steel insert. In addition to the elimination of the sharp bends and the adjusting of the tension in the handrail, the running of the handrail on its return run over the rollers and the

elimination of supporting guides for the return run of the handrail reduces handrail friction to a minimum. Also, the tension device has the further advantage that its large radius minimizes

5 the possibility of deformation of the handrail and thus widening it to such extent as to enable it to readily come off its guides. A seven foot radius has been found satisfactory in practice but this may vary.

10 As many changes could be made in the above construction and many apparently widely different embodiments of this invention could be made without departing from the scope thereof, it is intended that all matter contained in the above 15 description or shown in the accompanying drawings shall be interpreted as illustrative and not in a limiting sense.

What is claimed is:

20 1. A reverse bend tensioning device for the return run of a moving stairway handrail, said handrail being in the form of a continuous loop passing around a newel wheel at each end of the stairway and having a single wrap traction drive, said tensioning device comprising; a plurality of adjoining rollers over which the back of the handrail runs, said rollers being arranged in a long arc of large radius extending in a reverse bend from the upper newel wheel to well down the incline of the stairway; an arcuate support for 25 said rollers adjustably mounted on the stairway balustrade framework to enable the tension in the handrail to be adjusted; and a guide mounted on said arcuate support for laterally guiding said handrail on said rollers.

30 2. A tensioning device for the return run of a moving stairway handrail, said handrail being in the form of a continuous loop passing around a newel wheel at each end of the stairway and having a single wrap traction drive, the upper 35 newel wheel being driven, said tensioning device comprising; a plurality of closely spaced plastic rollers over which the back of the handrail runs, said rollers being provided with ball bearings and being arranged in a long arc of large radius

40 having its center below so as to provide a reverse bend for the handrail, said arc extending from the upper newel wheel to well down the incline of the stairway; an arcuate support for said rollers; a plate mounted on the stairway balustrade framework upon which said support is adjustably mounted so as to enable the tension in the handrail to be adjusted; and a short arcuate guide mounted on said arcuate support for laterally guiding said handrail on said rollers.

55 SAMUEL GUSTAVE MARGLES.
